FIG. I.

FIG. IV.

FIG. VI.

FIG. IV.

INVENTOR:
E. A. COWLES

By his attorney.

Carl R. Mueller.

UNITED STATES PATENT OFFICE.

EDWARD A. COWLES, OF CLEVELAND, OHIO.

MILLING-CUTTER.

1,391,097.

Specification of Letters Patent. Patented Sept. 20, 1921.

Application filed November 11, 1920. Serial No. 423,224.

To all whom it may concern:

Be it known that I, EDWARD A. COWLES, a citizen of the United States, residing at Cleveland, in the State of Ohio and Cuyahoga county, have invented a new and useful Improvement in Milling-Cutters, of which the following is a specification, the principle of the invention being herein explained and the best mode in which I have 10 contemplated applying that principle, so as to distinguish it from other inventions.

My invention relates to a milling cutter and more particularly to what I believe to be an improved manner of securing a detachable blade.

Being in the business of manufacturing milling cutters I am familiar with previous practices and with many other schemes which may never have been commercially demonstrated. It is common practice to provide the periphery of a cutter head with two kinds of slots alternatively arranged therearound. Blades are inserted in one set of slots and wedge pins cause the material between the slots to spring over against and bind the inserted blade.

I declare my knowledge of the fact that screws have been employed to directly engage a detachable blade, and have also been 30 passed through separate bushings which had a flat surface adapted to press against a blade. The former scheme does not accomplish the desired uniformity of expansion effect nor as firm a seating of the blade 35 whereas the latter is unduly expensive of manufacture and besides requires more trouble in assembly.

I propose to provide a cutter head with tapped openings communicating with one 40 set of slots and instead of driving in wedge pins provide expansive screws for cooperation with the tapped openings, the screws being integrally provided near their heads with a smooth tapered section purposed to 45 spread apart the walls of the slot between which it enters.

Adverting to the drawings:

Figure I is a side elevation of a milling cutter.

50 Fig. II is a plan view of Fig. I.

Fig. III is a vertical section taken on line III—III of Fig. II.

Fig. IV is a fragmentary plan view showing one modification of my invention.

55 Fig. V is a fragmentary plan view of another modified form.

Fig. VI is a fragmentary vertical section of Fig. V.

A cutter head 1 is fashioned with peripheral slots 2 in which are fitted blades 3. 60 Between certain, in this instance between each, pair of blades the head 1 is fashioned with additional somewhat narrower slots 4 each of which communicates at its middle with a conically surface bore 5. Extending 65 from the bottom of each of the bores 5 is a tapped opening 6 the threads of which are adapted for cooperation with the threaded shank 7 of an expansive screw having a tapered head 8 adapted to fit the bore 5. 70 The top of each screw is provided with a screw slot 9 to enable insertion and withdrawal of the screw by means of the screw driver. I believe that the application of a screw for the purpose of spreading the 75 resilient metal between any pair of blades is an improvement in the art, because it enables the binding action upon all the blades to be more uniformly affected by noticing the predetermined amount of insertion movement of any particular screw and then successively imparting the same amount of movement to all the other screws. 80

When very wide cutters are made it is preferable to employ a plurality of expansion screws, and in Fig. IV I have shown each slot 4 to be intersected by three screws 10. Figs. V and VI merely show a modification consisting of the substitution of a square key hole in the head of each screw. 90 Such screws 11 have heads 12 fashioned with squared holes 13.

I claim:

1. A milling cutter comprising a metal head fashioned with separated slots whereby to impart a limited resilience to a portion of said head between said slots, a blade wholly occupying one of said slots, said head being further provided with a tapped opening communicating with the other of said slots, and a screw adapted to cooperate with the threads of said opening and provided with a conical outer end surface adapted directly to engage and to spread apart the walls of the slot which 105 said screw enters.

2. A milling cutter comprising a head fashioned with radially extending slots, a blade seated in one of said slots, said head being also fashioned with a radially extending opening merging with the other of said slots and having its inner end tapped and 110

its outer end defined by a conical wall, and a screw provided with a tapered head and itself adapted during its insertion movement to spread the walls of the slot which 5 communicates with said opening.

3. A milling cutter comprising a head fashioned with a pair of slots each extending across from one side of the head to the other side and opening through its 10 peripheral surface, a blade occupying one of said slots, said head being also fashioned

with a partially tapped hole merging with the other of said slots, and a screw occupying said hole and provided with a wedge section adapted when driven home directly 15 to spread apart the walls of the slot which communicates with said hole whereby to compress the blade in the head.

Signed by me, this 10th day of November, 1920.

EDWARD A. COWLES.
